UNITED STATES PATENT OFFICE.

JOEL JENKINS, OF MONTCLAIR, NEW JERSEY.

GARMENT ATTACHMENT.

SPECIFICATION forming part of Letters Patent No. 729,769, dated June 2, 1903.

Application filed August 18, 1902. Serial No. 120,055. (No model.)

To all whom it may concern:

Be it known that I, JOEL JENKINS, a citizen of the United States, residing at Montclair, county of Essex, and State of New Jersey, have 5 invented a new and useful Improvement in Garment Attachments, of which the following is a specification.

My invention relates to improvements in attachments whereby a button or other garment- 10 engaging means may be securely but detachably fastened to the garment.

The invention contemplates a clip adapted to be fastened to a garment and provided with a button or other garment-engaging means.

15 The invention is illustrated in the accompanying drawings, in which—

Figures 1, 2, and 3 present front, back, and side views, respectively, of the preferred form of my improved device. Fig. 4 is a view similar to Fig. 3, with the jaws of the clip open to receive the garment. Figs. 5 and 6 show isometric views of the coating members of my clip. Fig. 7 is a view of a modification. Fig. 8 is an isometric enlarged view of the device 25 shown in Figs. 1 to 4, inclusive.

My invention contemplates a novel means of attaching so-called "bachelors' buttons" to garments, and also provides an effective, simple, and secure clip to be used with a cuff- 30 holder or other garment-engaging means to secure the same to the garment.

The device consists, essentially, of two members A and B, which are pivoted together and are provided with jaws having a series of teeth 35 at one extremity and with locking projections at the other extremity. The two members A and B are illustrated in detail in Figs. 5 and 6, respectively. The member A comprises the jaw a, with serrations at one extremity and 40 an extension a', which is connected with the part a by a shank a². In forming this member it is struck from sheet metal in the form of a blank, which is then bent to the shape shown by suitable dies. It will be noticed 45 that the shank a² is formed by cutting out a portion of the blank, leaving notches or openings a⁴ and with pintle projections a³, which are formed integral with the shank a². Furthermore, the shank a² is curved somewhat to 50 bring hinge-pintles a³ in proper position to engage the hinge-sockets of the member B. The member B comprises the part b, formed

with serrations to coöperate with the serrations of the part a, the extension b', which corresponds to the extension a' of the member A, and the offset b³. This member is provided with a central opening b², formed by cutting out the metal from the center of the blank and at the same operation cutting out tangs, which when bent to shape 55 form the hinge-knuckles b⁴ to receive the hinge-pintles a³ of the member A. The parts are assembled by slipping the extension a' through the opening b² and then turning down the tangs of the knuckles b⁴ over the 60 pintles a³. When thus assembled, these members will take the relative positions shown in Figs. 1 to 4, inclusive, and Fig. 8. A latch or locking and reinforcing bar C is fastened to the part a by means of a rivet c. This 65 latch is also provided with a struck-up projection c' to provide a finger-hold for said latch. Inasmuch as the parts a and a' lie upon opposite sides of the member B when 70 assembled, it is obvious that when the parts 75 are in the position shown in Fig. 3 the locking-bar C spans the hinge portion of the device and holds the parts firmly in closed position, and, at the same time, since this bar extends across the hinged portion when in 80 operative position, it also serves to reinforce and strengthen the device longitudinally.

In order to render this clip effective as a part of a garment fastener or supporter, a button, as D, may be riveted to one extremity of the member A, as at d, or one of the extensions a' or b' may be prolonged to form a cuff-holder, if desired, as shown in Fig. 7.

The device when completed provides a construction the parts of which may be readily 90 struck from sheet metal and easily assembled.

Many variations in the construction and relative arrangement of the parts of the device may be made without departing from the spirit of my invention.

What I claim, and desire to secure by Letters Patent, is—

1. In a garment attachment, garment-engaging means, comprising gripping-jaws hinged together; locking extensions for said jaws; a latch pivotally mounted on one of said extensions and adapted to span the hinged portion and engage the other extension and lock said jaws; and means on said

first-named extension to engage a supporting means.

2. In a garment attachment, garment-engaging means, comprising two members hinged together; gripping-surfaces at one end, and locking extensions at the opposite end of each of said members; a latch on one member, movable to span the hinged portion and to engage the other member to hold them in gripping position; and means on one member to engage supporting means.
3. In a garment attachment, garment-engaging means consisting of two members, each member comprising a gripping-jaw and a locking extension connected by an intermediate shank; pintles on the shank of one member; and hinge-knuckles forming a hinge connection for the members; a latch for holding the members in closed position adapted to act as a reinforce for the hinge means on one of said members for engaging a supporting strap or band.

4. In a garment attachment, garment-engaging means comprising gripping-jaws hinged together, extensions on said jaws, a locking and reinforcing bar pivotally mounted on one of said hinged members and adapted to be swung across the hinged portion to lock and reinforce said device.

5. In a garment attachment, engaging means comprising gripping-jaws hinged together, extensions on said jaws and a locking and reinforcing bar pivotally mounted on one jaw and adapted to be swung across the hinged portion to engage and lock the extension of the other jaw.

In witness whereof I have hereunto set my hand, this the 12th day of August, 1902, in the presence of two subscribing witnesses.

JOEL JENKINS.

Witnesses:

ARTHUR RUSSELL,
H. E. MATTHEWS.
